(57) **CLAIM**

The ornamental design for a film applicator tool, as shown and described.

DESCRIPTION

FIG. 1 is a perspective view of a film applicator tool, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlargement view of FIG. 1; and,

FIG. 10 is an enlargement view of FIG. 2.

The broken lines of even length depict portions of the film applicator tool in which the design is embodied that form no part of the claimed design. The dot-dash broken lines identify the boundaries of the enlarged areas.
